UNITED STATES PATENT OFFICE.

FREDERICK J. TODD, OF EGG HARBOR, NEW JERSEY, ASSIGNOR TO JOHN E. MARSDEN,
OF PHILADELPHIA, PENNSYLVANIA.

WINDOW-REGULATOR.

1,304,825.

Specification of Letters Patent.

Patented May 27, 1919.

Application filed August 4, 1917. Serial No. 184,476.

To all whom it may concern:

Be it known that I, FREDERICK J. TODD, a subject of the King of Great Britain, residing in Egg Harbor, county of Atlantic 5 and State of New Jersey, have invented a new and useful Window-Regulator, of which the following is a specification.

My invention relates to means for regulating the position of a window member, and 10 more particularly a window member of a vehicle, as an automobile, carriage or the like.

My invention resides in window regulator mechanism of a structure in which the window member is raised or lowered through a connection to a chain or belt co-acting with sprocket wheels or pulleys mounted upon a support or frame disposed within a pocket in the frame and so disposed or constructed 15 20 25 that the window driving mechanism may be detached from the window member and be removed as a unit from the pocket by withdrawal longitudinally therefrom, the support or frame carrying the actuating mechanism being detachably connected to the window frame within the pocket.

My invention resides also in window regulating mechanism which makes it possible conveniently to locate the driving knob or handle of the mechanism, especially where the window member to be moved is located at a seat or in such position that the driving knob or handle as usually located would be in position inconvenient for operation.

For an illustration of some of the many forms my invention may take, reference is to be had to the accompanying drawings, in which:

Figure 1 is a vertical sectional view, on 40 the line 1—1 of Fig. 2, through a window frame and pocket, as an automobile door, with parts of the mechanism shown in elevation.

Fig. 2 is a vertical sectional view taken 45 on the line 2—2 of Fig. 1.

Fig. 3 is a vertical sectional view showing the lower portion of Fig. 1 on enlarged scale.

Fig. 4 is a fragmentary sectional view on the line 4—4 of Fig. 3.

Fig. 5 is a face view of the upper end of the plate or frame supporting the driving mechanism.

Fig. 6 is a side elevational view of the locking plate.

Fig. 7 is a horizontal sectional view, partly 55 in plan, showing the detachable mounting of the lower end of the plate or frame supporting the driving mechanism.

Figs. 8, 9, 10 and 11 are modifications of detachable mountings or supports of the 60 lower ends of the plate or frame of the driving mechanism.

Fig. 12 is a side elevational view of window member driving mechanism for convenient location of the operating handle or 65 knob.

Referring to Figs. 1 to 7 inclusive, 1 represents a window casing or frame, such as an automobile door or the like, in which is vertically slidable in suitable guides the glass 70 window pane or window member 2. In the lower portion of the frame 1 is formed the pocket 3 formed between the side members 1 of the window frame, the bottom 4, the outside wall 5 and the inside wall 6, on 75 which latter may be disposed upholstery 7 or any other suitable decorative material, the member 6 being joined at its upper end to the transverse member 8 upon whose upper edge is the sill 9 secured by screws 10. 80 The sill 9 is spaced from the outside wall member 5 to form a space through which the window member 2 may be raised and lowered. The lower edge of the window pane or member 2 is received in the metallic 85 channel member 11, which holds it frictionally and from which it is readily removed. Secured to the channel member 11 is a plate 12 having the horizontally extending slot 13 enlarged at one end at 14 to allow insertion 90 and removal of the headed pin 15 secured to the sprocket chain 16 driven by the sprocket wheel 17 and passing over the idler sprocket wheel 18. A plate 19 has at its 95 upper end a horizontally projecting flange 20 engaging upon the upper end of the frame member 8 beneath the sill member 9. The plate 19 carries the bearing member 21 on which the sprocket 17 rotates. At its lower edge at 22, 22, Fig. 5, the plate 19 engages in the hooks or members 23 carried by the framework as by attachment to the lower edge of the frame member 8.

The lower sprocket wheel 18 rotates upon a bearing carried by the plate 24 engaging at 105 its lateral edges in vertical slots in the vertically extending members 25, 25, Figs. 3 and 7, secured upon the frame member 6. The

plates 19 and 24 are secured to each other by the strap or plate 26, whereby the plates 19 and 24 form a unitary structure or plate member or frame on which are mounted the 5 driving mechanism comprising the sprocket wheels and the sprocket chain.

Secured to the upper sprocket wheel 17 is the gear wheel 27 having the internal gear teeth 28 with which is constantly in mesh 10 the pinion 29 formed upon or secured to the rotatable and longitudinally movable shaft 30 which extends through the slot 31 which extends downwardly from the upper edge 15 of the frame member 8 to a point just below the shaft 30. On the inner side of the member 8 is the sleeve 32 supported in the bushing 33 having the flange 34 secured to the inner side of the frame member 8. Rotatable upon the sleeve 32 is the arm 35 to 20 which is pivoted at 36 the hand crank 37 having the handle 38. The crank 37 is attached by pin 39, Fig. 4, to the longitudinally movable shaft 30.

Secured to the plate 19 is the locking 25 plate 40 having the notches 41 between the teeth 42, Figs. 4 and 6, with which the teeth of the pinion 29 are adapted to mesh and thereby prevent rotation of the pinion 29 which in turn prevents rotation of 30 the sprocket 17, to thereby lock the window member 2 in any position, because the pinion remains in mesh with the internal gear 28. A spring 43 forces the shaft 30 toward 35 the inner side of the frame member 8 to cause the pinion 29 to engage the locking teeth 42 on the locking plate 40.

In the plate 19 is provided the opening 44, Fig. 5, in the outwardly projecting portion 19^a of the plate 19 for the pinion 29 to 40 allow it to mesh with and drive the internal gear 28.

The operation is as follows:

Suppose it be desired to raise the window member 2, the operator first presses 45 upon the handle 38, thereby pushing the shaft 30 inwardly to disengage the pinion 29 from the locking teeth 42 while maintaining mesh with the internal gear 28, this pressure being in opposition to the spring 50 43, which is now compressed. The crank 37 is then turned in suitable direction, rotating the shaft 30, which in turn rotates the pinion 29 which in turn rotates the gear 28 which drives the sprocket 17 which in 55 turn drives the chain 16 which carries with it the pin 15 which imparts an upward movement to the window member 2, the pin 15 moving longitudinally in the slot 13 as the member 2 approaches its uppermost 60 limit of travel. Upon release of the crank 37 the spring 43 expands and moves the pinion 29 laterally into engagement with the locking teeth 42, which accordingly prevents rotation of the pinion 29 and there- 65 fore of the gear 28 and so prevents move-

ment of the chain 16 which through the pin 15 retains the window member in any position to which actuated.

To lower the window member 2 the operation is the same except that the crank 37 70 is rotated in opposite direction, and in so doing the spring 18^a, connected with the lower sprocket wheel 18, is wound up so that when the window member 2 is again raised the spring 18^a assists in the raising 75 movement.

The operating mechanism is of such structure, as hereinbefore described, that it is readily demountable and removable from the pocket 3 within the framework. 80

This may be quickly done by removing the strip or sill member 9 and by removing the pin 39 and the screws which hold the flange 34 of member 33 to the member 8.

Thereafter the plate 19 with attached 85 plates 26 and 24 is raised upwardly, removing the plate 19 from the supporting members 23, and similarly raising the plate 24 upwardly through the slots in the members 25, 25, the sprocket and chain mechanism 90 and its operating mechanism being then lifted vertically through the upper end of the pocket 3, the shaft 30 rising through the vertically extending slot 31 which extends to the upper edge of the frame member 8, the 95 pin 15 and its head having first been removed through the enlargement 14 at the end of the slot 13 in the plate 12, which attaches the window member 2 to the chain 16.

By the construction described, therefore, 100 the entire window operating mechanism may be removed as a unit without removal of any of the frame members as 1, 5, 6 or 8, and may be adjusted or repaired and again readily re-inserted, by inserting the 105 plate 24 into the slots in the members 25 and the plate 19 into the holders or hook members 23.

Due to the construction described there is 110 effected an economy in time and labor, and furthermore, the upholstery 7 on the member 6 need not be removed, nor need the member 6 itself be removed.

In Fig. 8 is shown a modified arrangement for detachably supporting the lower 115 end of the driving mechanism. In this case the plate 24 has at its lower end a tongue 45 which is inserted into the aperture 46 in the plate 47 resiliently supported by springs 48 on the bolts 49 carried by the bottom frame 120 member 4.

In Fig. 9 the structure is similar, except 125 that the plate 24 has thereon two tongues or lugs 45^a engaging in apertures in the plate 47.

In Fig. 10 there is shown an upwardly opening hook member 50 secured at its lower end to the frame member 6 and in which the plate 24 engages.

In Fig. 11 the plate 24 is shown as held by 130

a screw 51 extending through the frame member 6 and engaging in the post 52 secured upon the bottom of frame member 4.

In some cases the window member 2 is located at the end of a seat in a carriage or automobile, or in other position such that the application of the operating handle for the driving mechanism would be inconveniently located if placed in the usual position substantially at the middle of the width of the window member 2.

To overcome this inconvenience I have provided a structure illustrated in Fig. 12, where the member 2 is shown at the end of a seat in a carriage or automobile. In this case the sprocket wheels 17 and 18 are, as before, mounted upon the plates 19 and 24 which are secured together by the plate 26, the plate 19 being received in the hooks or jaw members 23 and the plate 24 in the vertical slots in the members 25. As before, the plate 12 is attached to the window member 2 and co-operates with the pin 15 carried by the chain 16. In this case, however, a third sprocket wheel 53 is pivoted on the plate 19 forward of the sprocket wheel 17, the gear 28 in this case being attached to the sprocket wheel 53 and actuated by the pinion 29 actuated in turn by the operating lever 37. In this case the sprocket chain extends over the three sprocket wheels, and actuation of the gear 53 actuates the chain and through the pin 15 the window member 2 to raise and lower the same as before described, the pinion 29 serving to lock, by mechanism similar to that described in connection with Figs. 3 and 4, the window member 2 in any desired position.

By this structure the handle 37 is located forward in the more natural position to be operated by a person sitting beside the window member 2. The operator thus reaches forward to actuate the crank 37 which is forward of the person operating it, and not at the side of the operator, as would be the case if the crank 37 were located at the sprocket wheel 17.

This driving mechanism is also readily dismountable or removable as hereinbefore described in connection with the two wheel mechanism.

While I have herein disclosed sprocket wheels and a sprocket chain co-operating therewith, it will be understood that my invention is not limited thereto, but that there may be used in lieu thereof a belt, cord or the like, traveling upon suitable pulleys or suitably constructed wheels.

Certain of the subject matter herein disclosed relating to the actuating mechanism and lock is claimed in Letters Patent of the United States No. 1,274,471, granted me August 6, 1918.

What I claim is:

1. The combination with a window mem-

ber, of a frame within which the same is movable, said frame having a pocket into which said window member is movable, mechanism for actuating said window member comprising a chain, a detachable connection between said chain and said window member, wheels engaging said chain, means for actuating at least one of said wheels, a unitary support for said actuating mechanism, means holding said support at its upper end to said frame approximate the upper end of said pocket, and means detachably supporting said support at its lower end to said frame within said pocket.

2. The combination with a window member, of a frame within which the same is movable, said frame having a pocket into which said window member is movable, actuating mechanism for said window member comprising sprocket wheels and a chain, a detachable connection from the chain to the window member, means for rotating at least one of said sprocket wheels, a unitary support for said actuating mechanism, and means detachably holding the same approximate its lower end in said pocket, said actuating mechanism being removable as a unit from said pocket in the direction of movement of said window member.

3. The combination with a window member, of a frame in which the same is movable, actuating mechanism for said window member comprising a sprocket chain having a part movable vertically with said window member, sprocket wheels engaging the same, a connection from said part of said chain to said window member at substantially its middle, one of said sprocket wheels displaced laterally from the middle of said window member, and means permanently located adjacent said last named sprocket wheel for rotating the same.

4. The combination with a window member, of a frame in which the same is movable, actuating mechanism comprising three sprocket wheels disposed in a plane substantially parallel with the plane of movement of said window member, a chain engaging said wheels and having a part movable vertically with said window member, a connection from said part of said chain to said window member, two of said sprocket wheels disposed respectively at substantially the middle of said window member and to one side thereof, and means permanently located adjacent said laterally displaced sprocket wheel for rotating the same.

5. The combination with a window member, of a frame in which the same is movable, actuating mechanism for said window member comprising a sprocket chain, sprocket wheels engaging the same, a con-

- nection from said chain to said window member at substantially its middle, one of said sprocket wheels displaced laterally from the middle of said window member, 5 means for rotating said last named sprocket wheel, a unitary support for said sprocket wheels and chain, and means detachably supporting the same upon said frame.
6. The combination with a window member, of a frame in which the same is movable, actuating mechanism comprising three sprocket wheels disposed in a plane substantially parallel with the plane of movement of said window member, a chain 10 engaging said wheels, a connection from said chain to said window member, two of said sprocket wheels disposed respectively at substantially the middle of said window member and to one side thereof, means for 15 rotating said laterally displaced sprocket wheel, a unitary support for said sprocket wheels and chain, and means detachably supporting the same upon said frame.
7. The combination with a window member, of a frame within which the same is 20 movable, said frame comprising members spaced from each other to form a pocket into which said window member is movable, actuating mechanism for said window member comprising a sprocket wheel and a chain co-operating therewith, a detachable connection between the chain and said window member, means for rotating the sprocket wheel, a unitary support for said 25 wheel and chain, and means detachably holding said support approximate its lower end within said pocket, said actuating mechanism and the support therefor being removable as a unit from said pocket in 30 the direction of movement of said window member.
8. The combination with a window member, of a frame within which the same is 35 movable, said frame comprising members spaced from each other to form a pocket into which said window member is movable actuating mechanism for said window member comprising sprocket wheels one disposed below the other, a chain engaging said 40 sprocket wheels, a detachable connection from said chain to said window member, means for rotating one of said sprocket wheels, a unitary support on which said sprocket wheels are mounted, and means 45 detachably securing said support within said pocket adjacent said sprocket wheels, said sprocket wheels, chain and support being removable as a unit through one end of said pocket.
- 50 9. The combination with a window member, of a frame within which the same is movable, said frame comprising members spaced from each other to form a pocket into which said window member is 55 movable, a transversely extending sill spaced 60 from one of said members to leave a passage through which said window member is movable, actuating mechanism comprising a sprocket wheel and chain, a connection from said chain to said window member, a unitary support for said actuating mechanism detachably supported within said pocket beneath said sill, whereby upon removal of said sill said actuating mechanism may be removed as a unit upwardly 70 through one end of said pocket.
- 65 10. The combination with a window member, of a frame in which the same is movable, actuating mechanism comprising sprocket wheels and a chain having a part 75 movable vertically with said window member, a connection from said part of said chain to said window member at substantially its middle, and means permanently located at one side of said window member 80 for actuating one of said wheels to move said window member.
- 70 11. The combination with a window member, of a frame within which the same is movable, said frame having a pocket 85 into which said window member is movable, actuating mechanism for said window comprising sprocket wheels disposed one above the other, a chain actuated by said sprocket wheels and connected to said window member, means for actuating one of said sprocket wheels to actuate said chain, a unitary support for said wheels and chain, and means at the top and bottom of said unitary support detachably supporting 90 the same upon said frame.
- 75 12. The combination with a window member, of a frame within which the same is movable, said frame having a pocket 95 into which said window member is movable, actuating mechanism for said window comprising sprocket wheels disposed one above the other, a chain actuated by said sprocket wheels and connected to said window member, means for actuating one 100 of said sprocket wheels to actuate said chain, a unitary support for said wheels and chain, means at the top and bottom of said unitary support detachably supporting the same upon said frame, and a sill 105 on said frame extending across above said actuating mechanism and leaving a space through which said window member is movable, said actuating mechanism being removable as a unit from said pocket upon 110 removal of said sill.
- 80 13. The combination with a window member, of a frame in which the same is movable, said frame comprising walls 115 spaced from each other to form a pocket into which said window member is movable, window actuating mechanism comprising an operating member disposed exterior to one of said walls, a unitary support for said actuating mechanism, one 120
- 85 125
- 90 130

of said frame walls having an opening at one of its edges, and a mechanical connection from said operating member to said mechanism extending through said opening, said actuating mechanism being removable as a unit in a direction parallel to the movement of said window member through one end of said pocket and said mechanical connection rising through said opening.

14. The combination with a window member, of a frame in which the same is movable, said frame comprising wall members spaced from each other to form a pocket into which said window member is movable, actuating mechanism for said window comprising sprocket wheels and a coöperating chain, a connection from said

chain to said window member, a unitary structure for said wheels and chain supporting said wheels one above the other in said pocket, a transversely extending sill at the upper end of said pocket secured upon the upper end of one of said wall members and extending adjacent said window member over said actuating mechanism, removal of said sill permitting removal of said operating mechanism as a unit through the upper end of said pocket without access to the outer face of said one of said pocket walls.

In testimony whereof I have hereunto affixed my signature this 1st day of August, 1917.

FREDERICK J. TODD.
